SIMULATED WINDOW

Florence J. Sterling, Chicago, Ill., assignor to
Sterling-Freeland Industries, Inc., Chicago, Ill.,
a corporation of Illinois

Application December 11, 1948, Serial No. 64,879

4 Claims. (Cl. 240—10)

1

This invention relates to lighting and more particularly to a means for the employment of artificial light in such a way that the illusion of natural light or sunlight is created.

In many homes and apartments no provision has been made for an outside window where one is often-times desired. For example, as much time is spent at the sink in the kitchen in the average home, the housewife frequently prefers that a window be positioned over the sink, for various reasons, including that of the avoidance of being faced with a blank wall throughout a substantial portion of the day. In other fields, such as advertising and display, there is often-times a need to simulate the appearance of a window as accurately as possible. In industry locations, windows in various rooms, such as restrooms, are often not available, and it is desirable to provide as home-like and cheerful a room as possible.

Accordingly, it is an object of the present invention to provide a structure which will simulate that of an outside window, incorporating means therein for the employment of artificial light in such a way as to create the illusion of its receiving natural light.

A further object of the invention is the provision of structure for providing light in an apparently natural way, which light may be directed as desired.

A still further object of the invention is the provision of a relatively inexpensive and durable structure adapted for use in conjunction with a wall and which is adapted to transmit light therethrough to create the illusion of natural light.

These and other objects of the invention will become apparent from the following description taken in conjunction with the accompanying drawings, wherein:

Fig. 1 is a front elevation of the device with a Venetian blind in place;

Fig. 2, a front elevation with the Venetian blind raised;

Fig. 3, a section on the lines 3—3 of Fig. 1; and,

Fig. 4, a section on the lines 4—4 of Fig. 2.

With continued reference to the drawings a device constructed in accordance with the present invention is disclosed and includes a framework 10 of substantially rectangular configuration. The framework has side members 11 and 12 and upper and lower members 13 and 14. The members are preferably constructed of channel shaped sections, each having a leg 15 disposed inwardly of the framework and a leg 16 disposed outwardly thereof, connected by a web 17.

2

A substantially flat sheet member or back plate 18 having flanged edges 19 is attached to the leg 16 of the channel members of the framework by means of fasteners 20 passing through the members. It is apparent that the framework in combination with the backing plate provide a recess 21 between the inner leg members 15 of the framework. The surface of the framework which defines a portion of the recess 21 may have a reflecting surface such as a mirror, or be of a light shade.

Suitable light sources are positioned in the recess 21 and these are preferably of the tubular type well known in the art. Those disclosed include U-shaped tubular leg members 22 and 23 having their free ends positioned in the inner leg 15 of the channel member 11 of the framework. Their loops are received through apertures 24 of the inner legs 15 of the channel members 12.

Suitable electrical connectors are attached to the light and are received in a conventional plug 25 which may be connected to a source of electrical energy.

An elongated angle member 26 has a leg 27 attached to the leg 16 of the upper channel member 13 and has its leg 28 spaced from the web 17 of the channel member. Secured within the space is a supporting bar 29 of a Venetian blind type of shade 30.

The entire structure is adapted to rest on a sill or other support, or may be attached to a wall.

When the structure is positioned, an observer sees what appears to be a conventional window covered by a Venetian blind through which light is being transmitted. This creates the illusion of a window receiving natural light. The angle of the slats may be adjusted to direct the rays substantially downwardly or at another preferred angle.

Although various kinds of lights including tubular types may be used, a preferred variety has been found to be the cold-light type in order to protect the shade or blind from being exposed to an excessive amount of heat, and also to prevent the creation of unnecessary heat when this is undesirable, as for example, during the hot season of the year.

This invention is not limited to the construction in the various parts thereof, of any particular material, although sheet metal or plywood has been found to be preferable.

It is apparent that the invention contemplates a supporting framework for a shade, preferably of the Venetian blind type and which is adapted

to create the illusion of an outside window exposed to the natural light and which provides light for interior use.

It will be obvious to those skilled in the art that various changes may be made in the invention without departing from the spirit and scope thereof, and therefore the invention is not limited by that which is shown in the drawings and described in the specification, but only as indicated in the appended claims.

What is claimed is:

1. In combination a substantially rectangular framework of channel members including upper and lower and side members, a back for the framework comprising a substantially flat sheet member having flanged edge portions attached to the outer legs of the channel members, the sheet member in combination with the framework providing a recess, a plurality of tubular light members supported in the recess in spaced relation and having their end portions within one of the channel members, each of said light members consisting of a U-shaped tube extending transversely of the recess, electrical means attached to the light members and adapted to be connected to a source of electrical energy for energizing said light, an elongated angle member having one leg attached to a leg of the upper channel member and the other extending downwardly and spaced from a portion thereof, a slat type blind supported in the space between the leg of the elongated angle member and the framework channel member in order that the blind may be in a position to substantially cover the framework including the recess, means for selectively controlling the angle of said blind slats whereby the rays of the light members may be projected directly through the blind at different angles to vary the effect of the illumination and create the illusion of natural light.

2. In combination a substantially rectangular framework of channel members including upper and lower and side members, a back for the framework comprising a substantially flat sheet member attached to the channel members, the sheet member in combination with the framework providing a recess, one or more tubular light members supported in the recess and having their end portions positioned within the channel members, said light members extending transversely of the recess in zig-zag relation thereto, electrical means attached to the light members and adapted to be connected to a source of electrical energy for energizing said light members, an elongated angle member having one leg attached to a leg of the upper channel member and the other extending downwardly and spaced from a portion thereof, a slat type blind supported in the space between the leg of the elongated angle member and the framework channel member in order that the blind may be in a position to substantially cover the framework including the recess, means for selectively controlling the angle of said blind slats

whereby the rays of the light members may be projected directly through the blind at different angles to vary the effect of the illumination and create the illusion of natural light.

3. In combination a substantially rectangular framework of channel members including upper and lower and side members, a back for the framework comprising a substantially flat sheet member attached to the channel members, the sheet member in combination with the framework providing a recess, one or more light members supported in the recess extending transversely thereof, electrical means attached to the light members adapted to be connected to a source of electrical energy for energizing said light members, an elongated angle member having one leg attached to a leg of the upper channel member and the other extending downwardly and spaced from a portion thereof, a slat type blind supported in the space between the leg of the elongated angle member and the framework channel member in order that the blind may be in a position to substantially cover the framework including the recess, means for selectively controlling the angle of said blind slats whereby the rays of the light members may be projected directly through the blind at different angles to vary the effect of the illumination and create the illusion of natural light.

4. In combination a substantially rectangular framework including upper and lower and side members, a back for the framework comprising a substantially flat sheet member attached to the members, the sheet member in combination with the framework providing a recess, one or more tubular light members supported in the recess extending transversely thereof, electrical means attached to the light members adapted to be connected to a source of electrical energy for energizing said light members, an elongated member attached to the upper member and spaced from a portion thereof, a slat type blind supported in the space between the elongated member and the framework member in order that the blind may be in a position to substantially cover the framework including the recess, means for selectively controlling the angle of said blind slats whereby the rays of the light members may be projected directly through the blind at different angles to vary the effect of the illumination and create the illusion of natural light.
